Primary Examiner — Kelley A Donnelly(74) *Attorney, Agent, or Firm* — Haverstock & Owens LLP(57) **CLAIM**

I claim the ornamental design for a tool bag, as shown and described.

DESCRIPTION

FIG. 1 is a front elevation view of the tool bag;
FIG. 2 is a back elevation view of the tool bag;
FIG. 3 is a left side elevation view of the bag (the right side elevation view is a mirror image of the left side); and
FIG. 4 is a bottom elevation view of the tool bag.
FIG. 5 is a top elevation view of the tool bag in an open configuration.
FIG. 6 is a front perspective view of the tool bag; and
FIG. 7 is a front elevation view of the tool bag illustrating the front pocket in an open configuration.
The broken lines illustrate portions of the tool bag and form no part of the claimed design.
